UNITED STATES PATENT OFFICE

167,758

LOADER UNIT FOR FARM TRACTORS

John I. Michaels, Carl A. Loesch, Kenneth E. Haddock, and Charles J. Davis, Wichita, Kans., assignors to Mid-Western Industries, Inc., Wichita, Kans., a corporation of Kansas

Application May 23, 1952, Serial No. 19,850

Term of patent 14 years

(Cl. D14—3)

To all whom it may concern:

Be it known that we, John I. Michaels, Carl A. Loesch, Kenneth E. Haddock, and Charles J. Davis, citizens of the United States, residing at Wichita, State of Kansas, have invented a new, original, and ornamental Design for a Loader Unit for Farm Tractors, of which the following is a specification, reference being had to the accompanying drawings, forming a part hereof.

Fig. 1 is a three-quarter front perspective view of the loader unit for farm tractors, showing my new design, with the lifting arms in raised position for clarity.

Fig. 2 is a right hand side view of the loader unit, the dotted lines showing the relative position of the loader when mounted on a tractor, the lifting arms being shown in partially raised position.

Fig. 3 is a left hand side view of the loader, otherwise similar to Fig. 2, the lifting arms being shown in lowered position.

Fig. 4 is a front view of the loader with the lifting arms in a lowered position.

Fig. 5 is a rear view of the loader with the lifting arms in a lowered position.

Fig. 6 is a top plan view of the lower portion of the loader, and is taken along the line 6—6 of Fig. 2, the lifting arms having been removed.

Fig. 7 is a fragmentary view, partially in section, showing details of design, the section being taken along the line 7—7 of Fig. 4.

The dotted lines shown on the drawings are for illustrative purposes only.

We claim:

The ornamental design for a loader unit for farm tractors, as shown and described.

JOHN I. MICHAELS.
CARL A. LOESCH.
KENNETH E. HADDOCK.
CHARLES J. DAVIS.
